UNITED STATES PATENT OFFICE.

CHARLES J. HARRIS, OF BRIDGEPORT, CONNECTICUT, ASSIGNOR TO LOCOMOBILE COMPANY OF AMERICA, OF BRIDGEPORT, CONNECTICUT, A CORPORATION OF WEST VIRGINIA.

GARMENT-RACK FOR VEHICLES.

No. 895,751.

Specification of Letters Patent. Patented Aug. 11, 1908.

Application filed August 16, 1907. Serial No. 388,824.

To all whom it may concern:

Be it known that I, CHARLES J. HARRIS, a citizen of the United States, residing at Bridgeport, in the county of Fairfield and State of Connecticut, have invented an Improvement in Garment-Racks for Vehicles, of which the following description, in connection with the accompanying drawings, is a specification, like letters on the drawings representing like parts.

This invention pertains to a rack or holder for garments and the like to be used on a vehicle, such as an automobile or carriage.

The invention consists in various improvements over devices heretofore used with the same purpose in view and in features of construction and arrangement whereby the rack may be moved out of the way when not in use and may serve to hold a garment or the like securely in place when desired.

The character of the invention will be best understood by reference to the accompanying drawings, which show an illustrative embodiment.

In the drawings Figure 1 is a side elevation of a portion of the vehicle, as, for example, the front seat of an automobile; and Fig. 2 is an elevation of the construction shown in Fig. 1 and viewed from the left in the latter figure.

The seat shown in Fig. 1 has a bottom 5 and rear wall 6 which may be supplied with the usual cushions 7—7. Preferably countersunk or otherwise seated in the back cushion 7 is one or more metal tubes 8, which may be flattened at their lower ends and bent for attachment to the bottom 5. They may be further attached to the rear wall by stirrup straps 9. The upper end of each tube 8 is preferably bent into the form of an arc to supply a seat in which the down turned ends of the holding bar 10 may be reciprocated in a curved or other path. The specific form of holding bar shown in the drawings comprises the horizontal part 10 bent at its ends to enter the tubes 8—8. At its upper part each tube 8 has a slot 11, through which projects a pin or button 12 fixed in a bent end of the holding bar 10, said pins or buttons 12 serving to guide the bar 10 in its movement and to prevent the latter from being completely withdrawn from the tubes 8—8. Preferably the bent ends of the bar 10 fit sufficiently loosely in the tubes 55 8—8 so that the bar may drop by gravity

into the full line position shown in Fig. 1. In this position, the bar 10 is entirely out of the way.

When it is desired to place a garment or the like upon the holding bar 10, the latter 60 may be withdrawn to the dotted line position shown in Fig. 1 and the garment folded over the horizontal part of the bar. Thereupon the combined weight of the garment and the bar 10 will depress the latter and hold it so 65 as to engage the garment firmly between the bar and the top of the rear wall 6 of the seat.

Any practicable number of garments may be placed over the bar 10, and they will all be firmly held as just described, the capacity 70 of the preferred form of garment rack being limited only by the extent to which the bar 10 may be withdrawn in order to provide space between the position 14 of the bar and the rear part 15 of the seat.

This invention supplies many considerable advantages over constructions heretofore used for the same general purpose, which will be apparent to those familiar with the art.

The specific illustrative embodiment may be variously changed and modified without departing from the proper scope of this invention; and it is to be understood that the features of the invention are not mutually 85 indispensable, since they may be used to advantage separately.

Claims:

1. In a garment rack, the combination of telescoping parts relatively movable on a 90 curved path; and means to support one of said parts.

2. The combination of a vehicle seat; slidably supported garment holding means normally held by gravity close to a part of said 95 seat; and a support for said means.

3. The combination of a vehicle seat; and automatically collapsible garment holding means arranged to move between a position spaced from the seat to a position proximate 100 the top of the seat.

4. The combination of a vehicle seat having a back cushion; and collapsible garment holding means resting normally in the angle between the top of said cushion and the top 105 of the rear wall of the seat and adapted to bind the garment against the seat.

5. The combination of a vehicle seat; a collapsible and expandible garment holder; and combined supporting and guiding means 110

for said holder, the latter being automatically collapsible in relation to said means to hold a garment against the rear of the seat.

6. The combination of a vehicle seat; a pair of tubes supported thereby; and a garment holding rod having its ends bent to telescope in said tubes.

7. The combination with a vehicle seat of a garment holder; and a support therefor on one side of the seat-back, said holder and support coöperating to permit the former to be moved to the other side of the seat back.

8. The combination with a cushioned vehicle seat, of a collapsible garment holder; and a support therefor concealed between the cushion and seat, the holder and support coöperating to permit the former to rest

when collapsed proximate the seat, the garment holder being adapted to bind the garment against the seat.

9. The combination with a vehicle seat, of a collapsible garment holder above the seat, and a support therefor, said holder and support coöperating to permit the former to be expanded to receive a garment and to be collapsed to a position of comparative retirement by gravity.

In testimony whereof, I have signed my name to this specification, in the presence of two subscribing witnesses.

CHARLES J. HARRIS.
